UNITED STATES PATENT OFFICE

166,582

TOY HORSE

Robert H. Wendt, Evanston, Ill.

Application December 22, 1949, Serial No. 6,778

Term of patent 14 years

(Cl. D34—15)

To all whom it may concern:

Be it known that I, Robert H. Wendt, a citizen of the United States, residing at Evanston, in the county of Cook and State of Illinois, have invented a new, original, and ornamental Design for Toy Horse of which the following is a specification, reference being had to the accompanying drawings forming part thereof.

Fig. 1 is a side elevational view of a toy horse showing my new design;

Fig. 2 is a top plan view; and

Fig. 3 is a front elevational view.

I claim:

The ornamental design for a toy horse, as shown.

ROBERT H. WENDT.
